DIAPER HOLDER

George F. Koury, Metairie, La., assignor to Pantasote Company, New York, N.Y.

Filed Apr. 5, 1971, Ser. No. 131,574

Term of patent 14 years

Int. Cl. D24—04

U.S. Cl. D83—1 A

Fig. 2

Fig. 4

FIG. 1 is a top plan view of a diaper holder, formed of flexible sheet material such as flexible translucent plastic sheet material, embodying my new design;

FIG. 2 is a side edge view;

FIG. 3 is a bottom plan view; and

FIG. 4 is a section along 4—4 of FIG. 1.

I claim:

The ornamental design for a diaper holder, substantially as shown and described.
